6 Claims. (Cl. 274—10)

1

The present invention relates to record changing mechanism for phonographs and more particularly to that type of mechanism in which a record magazine positioned over the turntable is adapted to support a sequence of records in stacked formation from which one record at a time may be laterally displaced and thereby be deposited into playing position on the turntable. Such phonographs necessitate means for retaining the magazine records in their initial position in the magazine during the displacement and release of the bottommost record therefrom. Hitherto such means generally comprised a cranked or offset central post projecting upwardly from the turntable, the sequence of records to be played being threaded in stacked formation on said post and supported by the offset thereof. The dispensation with a central post of this nature will, however, facilitate the handling of the phonograph. It is obviously much more convenient to load the magazine by placing the sequence of records in a container fitting to the records than to thread them one by one onto a post. The difficulty encountered when constructing such a device is, however, to provide an effective stop means that will prevent the lateral displacement of all records in the magazine except the bottommost one during a record changing operation. This difficulty is greatly enhanced when it is desired that the phonograph shall be able to play a sequence of records of various sizes; besides this, consideration must be given to the fact that not all records are plane, it sometimes occurring that records are somewhat warped owing to undue exposure to heat.

It is an object of the invention to provide means for overcoming these difficulties. The invention comprises a lateral stop means positioned in alignment with the direction of displacement of the bottommost record in the magazine and adapted to permit a lateral displacement and release of the said bottommost record, but at the same time impede a displacement of at least the bottommost record but one in the magazine. The main characterizing feature of the invention is that the stop means is adapted to coact with a member, which under the influence of resilient pressure derived from a spring or the like is normally held in such a position that one end thereof will abut the underside of the bottommost record in the magazine, the other end thereof being normally held at a substantially constant distance above the upper surface of the bottommost record in the magazine.

So that the invention may be easily understood 55

2

and readily put into effect a preferred form thereof will now be described for illustrative purposes only, reference being had to the accompanying drawings in which:

- 5 Fig. 1 is a diagrammatic plan view of the mechanism according to the invention,
Fig. 2 is a diagrammatic side view of same,
Fig. 3 is a similar view to Fig. 2, showing another operative position of the mechanism,
10 Fig. 4 is a diagrammatic side view of a modified form of the lateral stop means according to the invention,
Fig. 5 shows the same mechanism as shown in Fig. 4, but as seen from above, and
15 Fig. 6 is a diagrammatic side view of a modified form of the invention.

With reference now to the drawings:

The reference numeral 1 represents a batch or sequence of records to be played. The batch 1 is supported by three support members 2, 3 and 4, the supporting members 2 and 3 being carried by standards 5 and 6, respectively, projecting uprightly from the bottom plate of the phonograph, not shown in the drawings. The supporting member 4 comprises a central post projecting upwardly from the centre of the turntable of the phonograph, said post being adapted to revolve with the turntable or to be motionless. The batch 1 of records is guided laterally by three guide members 7, 8 and 9, of which the members 7 and 8 comprise rounded off cones projecting upwardly from standards 5 and 6, respectively. The member 9 is supported by a third standard 10 mounted on the bottom plate of the phonograph, not shown. The guide member 9 does not extend to the bottommost record in the magazine. According to the invention there is below the member 9 a suitably shaped, movable lateral stop means 11 (see Fig. 2). The lateral stop 11 is mounted on a pivot pin 12 and elongated for providing an extension 13. The lateral stop 11 and its extension 13 are rotatable about the pin 12 and rotate in a slot 14 provided in the standard 10. The lateral stop 11 and its extension 13 are 20 under the control of a spiral spring 15 which is positioned in an enlargement 16 of the slot 14 provided about the pin 12. This spring tends to rotate the stop 11 anticlockwise, so that the extension 13 will engage the underside of the bottommost record in the magazine with a slight resilient pressure, as will be apparent from Fig. 2. Thereby the end of the lateral abutment 11 will normally always be situated a constant distance above the plane of the upper side of the said low- 25

be somewhat warped owing to undue exposure to the heat of the sun or the like. When there is no record on the supporting members, the lateral stop 11 will be rotated to such an extent clockwise by the spiral spring 26 as permitted by the limiting surface 16 of the slot 14. Through the standards 5 and 6 extend rotatable shaft members 17 and 18 respectively. Each of these shafts 17 and 18, respectively, is provided immediately above the support 2 with a wing member 19 and 20 respectively, the wing members being adapted to displace the bottommost record in the magazine laterally towards the left on rotation of the shafts 17 and 18. The wings 19 and 20 are movable in recesses 21 and 22, respectively, provided in the conical guide members 7 and 8, respectively.

The above described mechanism operates in the following manner:

When the phonograph is to be loaded, records are placed in the container or magazine, whose bottom comprises the supporting members 2, 3 and 4, and whose sides comprise the guide members 7, 8 and 9. The mechanism then assumes the appearance illustrated in Figs. 1 and 2. When a new record is to be deposited onto the turntable, the shaft members 17 and 18 are rotated by the intermediary of record changing mechanism (not shown in the drawings)—shaft 17 anti-clockwise and shaft 18 clockwise—whereby the wings 19 and 20 displace the bottommost record in the magazine toward the left until the central hole therein reaches the central post 4 and the edge thereof simultaneously leaves the support members 2 and 3. The record will then glide down the central post 4 onto the turntable (not shown). On displacement of the record to the left, the left hand edge of the record will pass underneath the lateral stop 11. The left hand stop member however obstructs the passage of the bottommost record but one, so that the latter cannot accompany the bottommost record on its lateral travel. When dropping from the magazine to the turntable the record retains engagement with the member 13, and rotates the latter and the lateral stop 11 about the pin 12 against the action of the spiral spring 26 disposed about the said pin. Fig. 3 shows the relative positions of the magazine and the various parts of the mechanism during a record changing operation immediately before the member 13 slips out of contact with the left hand edge of the record.

When a falling record reaches the turntable the lateral stop 11 and the member 13 are urged back into normal position (Fig. 2) by their spring. The wings 19 and 20, which during the fall of the record have assumed the position shown in Fig. 3, are returned to the position shown in Fig. 2 by record changing mechanism, not shown in the drawings, whereby the sequence of records in the magazine, which during the falling of the record was supported by the wings 19 and 20 and the central post 4 (Fig. 3), again falls onto the support members 2 and 3. All members have thus returned to the position shown in Fig. 2, and the next record changing operation may take place in a manner analogous to that described above, as soon as the changed record has been completely played.

When all records in the magazine have been played, they may be removed by lifting them in such a manner that their right hand edge first comes above the supports 2 and 3, until the central hole of the records has left the central post

4. It is also possible to mount the central post 4 detachably for facilitating the removal of the records.

By arranging the members 9, 11 and 13 movable in an upward direction one may, however, enable the records to be lifted straight up, when they are to be removed.

Figs. 4 and 5 show a mechanism modified for this purpose. In this modification of the invention the standard 10 is provided with two slots 14 and 23. Within the one slot 14 the lateral stop 11 and its extension 13 are rotatably mounted about a pin 12. A spiral spring 26 retains the lateral stop when not in contact with a record, in such a position in which it is turned somewhat in anti-clockwise direction from the position it assumes when a sequence of records is placed on the supports provided therefor. From this latter position the lateral stop 11 and the extension 13 may be rotated both clockwise and anti-clockwise. In the other slot 23 the guide member 28 is rotatably mounted on a pin 24. The member 28 is held in such a normal position by a spring 27 that the underside of the member 28 will abut a pin 25 provided on the standard 10. Figs. 4 and 5 show the position of the members of the mechanism at that moment when a sequence of records is about to be lifted from the turntable (not shown). At the moment illustrated in the drawings, the lateral stop 11 and the extension 13 have been urged aside by the batch of records 1, whilst the member 28 is just about to be swung back. When the batch of records is removed, both the member 28 and the lateral stop 11 are drawn back to their respective normal positions by their respective spiral springs 26 and 27.

During the falling of the record onto the turntable, the member 13 exercises a retarding effect on the left hand side of the record. The record is therefore always prone to fall onto the turntable in an askew or inclined position, which might cause a noisier engagement of the falling record and the turntable or the record already on the turntable than if the record were allowed or caused to retain its horizontal position whilst falling. In order to counteract such a tendency, the central pin 4 (see Fig. 6) may incline towards the left hand side of the record or towards that point in which the member 13 and the lateral stop 11 are positioned. The record will then have a tendency to fall with its left hand edge foremost, which tendency, however, will be balanced or neutralized by the retarding effect of the member 13. In this case the central pin 4 must obviously be fixed, i. e., not be rotatable with the turntable.

If a phonograph according to the invention is to be used for the changing of records of various diameters, the standards 5, 6 and 7 must be movable, so that they may be adjusted to various distances from the point of the central pin 4 according to the various sizes of the records. A common adjusting member adjustable to definite positions is then preferably provided.

The mechanism according to the invention may advantageously be used for automatically stopping the phonograph when all records in the magazine have been played. For this purpose the member 13 is adapted to assume a somewhat higher position when there are no records on the supports than when actuated by a record. When all the records in the magazine have been played, the member is urged into this higher position. Thereby it may be caused to actuate any well

known arrangement adapted to impart an impulse to a stopping mechanism after the last record in the batch has been played.

Although only a limited number of forms of the above invention have been described, it is obvious that various modifications thereof may be carried out within the scope of the invention and the appended claims.

What I claim and desire to secure by Letters Patent is:

1. In an automatic record changing mechanism for phonographs in which a sequence of records to be deposited one at a time onto the turntable of the phonograph are supported in stacked formation in a magazine over the turntable and in which the bottommost record in the magazine is laterally displaced in the course of every record changing operation and thereby released from the magazine and dropped onto the turntable, in combination, an upstanding support, a pin carried by said support, an asymmetric crescent member rotatably mounted intermediate its ends on said pin, spring means for normally retaining said asymmetric crescent member with its recess facing the record magazine and in such a position that the lower end of said crescent member will normally abut the underside of the said bottommost record and thereby hold the upper end thereof just above the upper surface of said bottommost record in the magazine, so that the upper end will permit a lateral displacement of said bottommost record into said recess but prevent a lateral displacement of the record above said bottommost record, stationary abutment means for limiting the rotation of said spring actuated crescent member when the magazine is empty, a second pin carried by said support and positioned adjacent the perimeter of the batch of records in the magazine and extending substantially at right angles to the axis of said batch of records, a guide member extending inwardly to a point substantially above the upper tip of said crescent member in its normal position with the records in the magazine and mounted for rotation on said second pin, a stop for said guide member, and spring means for urging said guide member against said stop therefor.

2. In an automatic record changing mechanism for phonographs in which a sequence of records to be deposited one at a time onto the turntable of the phonograph are supported in stacked formation in a stationary magazine over the turntable and in which the bottommost record in the magazine is laterally displaced in the course of every record changing operation and thereby released from the magazine and dropped onto the turntable, in combination, a support at one side of the magazine, a lateral stop member pivotally carried by the support about a horizontal axis and permitting lateral displacement of said bottommost record but preventing displacement of at least the record above said bottommost record in the magazine, and said lateral stop member having means contacting the underside of the lowermost record in the magazine to settle the position of the lateral stop member in order to hold said member at a substantially constant distance above the upper surface of the undermost record in the magazine.

3. In an automatic record changing mechanism for phonographs in which a sequence of records to be deposited one at a time onto the turntable of the phonograph are supported in stacked formation in a stationary magazine over the turntable and in which the bottommost rec-

ord in the magazine is laterally displaced in the course of every record changing operation and thereby released from the magazine and dropped onto the turntable, in combination a support at one side of the magazine, a pin carried by said supports, an asymmetric crescent member arranged substantially at right angles to the plane of records and with a circular recess between the two tips of the crescent member normally facing the records in the magazine, said asymmetric crescent member being rotatably mounted on said pin at a point substantially diametrically opposite to said recess, and spring means for normally retaining said asymmetric crescent member with its lower tip against the underside of said bottommost record and thereby holding the upper tip of said crescent member just above the upper surface of said bottommost record, the upper tip thus allowing a lateral displacement of the bottommost record into said recess but preventing a lateral displacement of the record above said bottommost record, said asymmetric crescent member by rotating against action of said spring means permitting the bottommost record to drop onto the turntable.

4. In an automatic record changing mechanism for phonographs in which a sequence of records to be deposited one at a time onto the turntable of the phonograph are supported in stacked formation in a stationary magazine over the turntable and in which the bottommost record in the magazine is laterally displaced in the course of every record changing operation and thereby released from the magazine and dropped onto the turntable, in combination a support at one side of the magazine, a pin carried by the support, an asymmetric crescent member arranged substantially at right angles to the plane of records and with a circular recess between the two tips of the crescent member normally facing the records in the magazine, said asymmetric crescent member rotatably mounted on said pin at a point substantially diametrically opposite to said recess, and spring means for normally retaining said asymmetric crescent member with its lower tip against the underside of said bottommost record and thereby holding the upper tip of said crescent member just above the upper surface of said bottommost record, the upper tip thus allowing a lateral displacement of the bottommost record into said recess but preventing a lateral displacement of the record above said bottommost record, said asymmetric crescent member by rotating against action of said spring means permitting the bottommost record to drop onto the turntable, and stationary abutment means for limiting the rotation of said spring actuated crescent member when the magazine is empty.

5. In an automatic record changing mechanism for phonographs in which a sequence of records to be deposited one at a time onto the turntable of the phonograph are supported in stacked formation in a stationary magazine over the turntable and in which the bottommost record in the magazine is laterally displaced in the course of every record changing operation and thereby released from the magazine and dropped onto the turntable, in combination a support at one side of the magazine, a pin carried by the support, an asymmetric crescent member arranged substantially at right angles to the plane of records and with a circular recess between the two tips of the crescent member normally facing the records in the magazine, said asymmetric

crescent member rotatably mounted on said pin at a point substantially diametrically opposite to said recess, spring means for normally retaining said asymmetric crescent member with its lower tip against the underside of said bottommost record and thereby holding the upper tip of said crescent member just above the upper surface of said bottommost record, the upper tip thus allowing a lateral displacement of the bottommost record into said recess but preventing a lateral displacement of the record above said bottommost record, said asymmetric crescent member by rotating against action of said spring means permitting the bottommost record to drop onto the turntable, and stationary abutment means for limiting the rotation of said spring actuated crescent member when the magazine is empty to approximately the same position it normally assumes when the magazine is loaded.

6. In an automatic record changing mechanism for phonographs in which a sequence of records to be deposited one at a time onto the turntable of the phonograph are supported in stacked formation in a stationary magazine over the turntable and in which the bottommost record in the magazine is laterally displaced in the course of every record changing operation and thereby released from the magazine and dropped onto the turntable, in combination a support at one side of the magazine, a pin carried by the support, an asymmetric crescent member arranged substantially at right angles to the plane of records and with a circular recess between the two tips of the crescent member normally facing the

records in the magazine, said asymmetric crescent member rotatably mounted on said pin at a point substantially diametrically opposite to said recess and spring means for normally retaining said asymmetric crescent member with its lower tip against the underside of said bottommost record and thereby holding the upper tip of said crescent member just above the upper surface of said bottommost record, the upper tip thus allowing a lateral displacement of the bottommost record into said recess but preventing a lateral displacement of the record above said bottommost record, said asymmetric crescent member by rotating against action of said spring means permitting the bottommost record to drop onto the turntable, stationary abutment means for limiting the rotation of said spring actuated crescent member when the magazine is empty, and a guide member positioned vertically above said crescent member and extending inwardly to a point substantially above the upper tip of said crescent member in its normal position with records in the magazine.
